United States Patent Office

Des. 209,126

Patented Oct. 31, 1967

209,126

POUR-IN TYPE BEVERAGE MAKER

John C. Martin, Springfield, Ill., assignor to Bunn-O-Matic Corporation, Springfield, Ill., a corporation of Delaware

Filed Mar. 2, 1967, Ser. No. 6,028

Term of patent 14 years

(Cl. D94—3)

FIG. 2

FIG. 1 is a perspective view looking from the top, front and left sides of a pour-in type beverage maker embodying my design.

FIG. 2 is a perspective view thereof looking from the top, rear and right sides.

I claim:

The ornamental design for a pour-in type beverage maker, substantially as shown and described.
